DEVICE FOR SHARPENING CUTLERY

Johan Fredrik Robert Karlström, Stockholm, Sweden, assignor to Aktiebolaget Electrolux, Stockholm, Sweden, a corporation of the Kingdom of Sweden

Application October 17, 1945, Serial No. 622,723
In Sweden October 24, 1944

11 Claims. (Cl. 51—241)

1

This invention relates to domestic appliances, and more particularly to devices for sharpening cutlery, such as knives, for example, and provisions for mounting devices of this type in working position.

In known devices for sharpening cutlery a grinding disc is provided which is intended to grind opposite faces of the knife edge in succession so that the knives have to be reversed a number of times in order that the knife edge shall be uniformly ground on both faces and that the sharpening shall be completed. On the other hand other sharpening devices have been proposed for grinding both faces of the edge simultaneously but such devices are in the main too complicated for domestic use.

The main object of this invention is to provide a sharpening device which is suitable for domestic use and which may be applied to a domestic machine having a readily accessible rotating member.

The novel features which are believed to be characteristic of the invention are set forth with particularity in the claims. The invention, both as to organization and method, together with the above and other objects and advantages thereof, will be better understood by reference to the following description.

According to the present invention the device for sharpening cutlery, such as knives, includes a grinding disc intended to be positively rotated relatively to the knife or the like to be ground and having around its periphery a deep groove which is acute angled at its base and is of fixed dimensions and is intended for the simultaneous grinding of the two faces of the knife edge.

The base of the groove of the grinding disc is formed with a fine clearance, which clearance may be filled with a material, such as paper or the like, which is innocuous to the knife edge. The grinding disc may be formed throughout of grinding material or the walls of the groove may be provided with grinding material secured thereto.

In a preferred construction the grinding disc or wheel is connected with a driving roller which is arranged to be rotated by frictional contact with a rotatable member. For example, the driving roller may be pressed against the edge of a rotatable container of a kitchen machine of known type. In such a case a support for the grinding disc and driving roller may comprise a resilient mounting which due to its inherent resiliency retains the driving roller pressed against the edge of the container.

2

The invention will be hereinafter more fully described with reference to several embodiments thereof which by way of example are illustrated in the accompanying drawing, in which:

Fig. 1 shows in side elevation the upper portion of a food mixing or kitchen machine having a sharpening device embodying the invention mounted thereon;

Fig. 2 shows in plan view the same machine and sharpening device;

Fig. 3 shows the device in plan view on an enlarged scale with the grinding wheel and the driving roller in section;

Fig. 4 shows a detail of the mounting of the stirrup in the frame of the kitchen machine;

Fig. 5 shows in front elevation the grinding wheel, with one half removed; and

Fig. 6 shows another embodiment of the grinding wheel in section, also with one half removed.

Referring to Figs. 1 and 2, a rotatable container of a so-called kitchen machine of known type is designated by 10. The machine frame carries a swingable arm 11 which is preferably moved into an inoperative position during grinding by being swung prior to grinding into the position shown in Figs. 1 and 2.

The grinding member of the sharpening device comprises a grinding wheel 12 and a driving roller 13 which are mounted for rotation on a support 14. The grinding wheel 12 consists of two halves 15, 16, which are held together by screw threads 17. The driving roller 13, which is preferably made of rubber, may also be secured by threads 18 to a boss 19 of the disc 15 but, if desired, it may be fastened in any other way, for instance by being vulcanized thereon. Since the diameter of the grinding wheel is larger than that of the driving roller, the peripheral speed of the grinding wheel will be greater than that of the container.

The support 14 consists of a resilient bracket or stirrup having its two ends formed as arms lying in planes extending at right angles to each other. One arm 20 forms a journal or spindle 45 rotatably supporting the grinding member and the other arm 21 is utilized to mount the bracket or the stirrup on the machine frame. The grinding member is held in position on the journal 20 by spring-rings 22 and 23. The grinding member cannot be released from the journal until the disc 16 has been unscrewed from the disc 15, thus making the spring-ring 23 accessible.

The arm 21 of the bracket or stirrup is enveloped in a rubber sleeve member 24 which positions the stirrup securely in a corresponding aper-

ture 25 in the machine frame. In the kitchen machine shown in Figs. 1 and 2 an already existing aperture is utilized for this purpose, the aperture becoming available by removing a scraping member therefrom when the grinding device is to be used. When the arm 21 with the rubber sleeve member 24 thereon has been forced into the aperture 25 with the bracket or stirrup in the position shown in Figs. 1 and 2, the arm 21 is held in position due to the rubber sleeve member 24 being compressed between the arm and the rim of the aperture and pressing resiliently against both elements. The driving roller 13 mounted on the other end of the stirrup is thus pressed against the container edge. On account of the elasticity of the sleeve member 24, the support is able to pivot slightly about the arm 21 even when the container edge may be slightly non-circular in shape. This mounting, however, provides sufficient friction to prevent the stirrup from becoming loosened from its position other than when the operator intentionally releases it manually. The sleeve member 24 may be suitably connected to the arm 21, as by vulcanization thereto, for example.

If desired, the sleeve member 24 may also form a bearing for the arm 21, in which case it desirably may be formed of metal, synthetic resin or similar material. In order that such a sleeve member will be held in position sufficiently tightly to insure the driving roller exerting the requisite pressure, the outer guiding surface 26 of the sleeve member 24 located in the aperture 25 should be made substantially shorter than the extent the arm 21 is supported in the sleeve member 24. This construction also locks the sleeve member 24, at the same time allowing the stirrup or bracket 14 to swing in a horizontal plane about the arm 21.

The inherent resilient mounting for the bracket or support 14 may, if desired, be replaced by a spring controlled pivoting arrangement between the arm 21 and the main portion of the stirrup.

In the embodiment shown in Fig. 6, the two discs 15 and 16 of the grinding wheel are constructed with inlaid grinding material 27 of Carbide or similar material. In the embodiment shown in Fig. 3, however, the grinding material consists of two annular-shaped pieces 28 of sandpaper or emery cloth. The grinding wheels 15 and 16 are preferably made of synthetic resin or similar material which in and of itself may serve as a bearing element at 20. Preferably the material is of the self-lubricating type since it cannot be assumed that this bearing will be lubricated.

Due to the fact that the grinding wheel, as shown in Fig. 1, is located externally of the outer face of the container, any powder or the like resulting from grinding will not fall into the container.

In grinding a knife or the like it is held by the handle and the edge of the knife blade is moved down into the acute angled groove 29 which extends about the rotating grinding wheel and is so formed that the edge of the knife is then ground on its two faces. The extreme edge is protected by the grinding material being covered at the base of the groove by rings 30 of paper or similar material.

In view of the foregoing it will now be understood an improved kitchen utility appliance has been provided comprising a base having a driving member for rotating an upright vessel 10 about a vertical axis. The bracket 14 having

spaced apart ends 20 and 21 is disposed so that the driven roller 13 and rotatable element 15 connected thereto are carried by the end portion 20. The end portion 21 is supported at a region outside the vessel 10 by structure associated with the base of the kitchen appliance, the bracket 14 being movable about such region at the vicinity of the sleeve member 24.

When the driven roller 13 is moved into frictional engagement with the vessel 10 while the latter is rotating, rotating movement is imparted to the rotatable element 15 about an axis at an angle with respect to the vertical axis of rotation of the vessel 10. As best seen in Fig. 2, the driven roller 13 is adapted to be moved into frictional engagement with an exterior surface of the vessel 10 at the top open edge thereof to impart rotating movement to the element 15 connected to the roller.

In the embodiment of the invention shown and described above the element 15 forms a knife sharpening accessory comprising grinding disc structure which provides an annular groove having opposing faces containing abrasive material. The roller 13 and disc 15 are rotatably carried by the arm 20 which is substantially perpendicular to the arm 21. The resilient sleeve member 24 is disposed about the arm 21 which is adapted to fit snugly in the recess of a part serving as a support. In this way a resilient mounting is provided for the bracket 14 so that, when the knife is pressed downwardly in the groove with the edge thereof extending horizontally, the frictional engagement between the vessel or driving member 10 and roller 13 is increased. Further, the sleeve member 24 of elongated form is of such size and so positioned that the inner contact surface thereof with the arm 21 is longer than the outer contact surface thereof with the wall of the recess.

The disc structure 15 comprises a plurality of parts which provide a relatively deep groove. The opposing faces of the groove contain abrasive material and form an acute angle of such size that, when a knife or other piece of cutlery is positioned with the knife edge directed toward the bottom of the groove and such edge in its lengthwise direction is closely adjacent to or in a plane substantially normal to the axis of rotation and at the apex of the groove, both sides of the knife edge are conveniently adapted to be subjected to abrasive action by the material at the opposing faces to effect sharpening of the knife edge. As best seen in Fig. 6, the separating member 30 prevents the opposing faces from being brought into abutting relation and keeps the abrasive material at such faces from coming into intimate contact at the apex of the groove.

While specific embodiments of the invention have been shown and described, it is to be understood that this has been done for the purpose of illustration only and that the scope of the invention is not to be limited thereby but is to be determined by the appended claims when interpreted as broadly as the prior art will permit.

What is claimed is:

1. A device for sharpening cutlery, such as knives, for example, comprising a rotatable driving member, a driven roller which is adapted to frictionally cooperate with the driving member, grinding disc structure connected to the driven roller for rotation about its axis, said structure including a plurality of parts constructed to provide a relatively deep groove about the periphery thereof, the opposing faces of the groove con-

taining abrasive material and forming an acute angle of such size that, when a knife or other piece of cutlery is inserted therebetween with the knife edge directed toward the bottom of the groove and such edge in its lengthwise direction is closely adjacent to or in a plane substantially normal to said axis at the apex of the groove, both sides of the knife edge are conveniently adapted to be subjected to abrasive action by the material at the opposing faces to effect sharpening of the knife edge, a separating member for said parts which is formed and arranged to prevent the opposing faces from being brought into abutting relation and keep the abrasive material at such faces from coming into intimate contact at the apex of the groove, an element upon which the roller is rotatably mounted, and means for resiliently mounting the element so that, when a knife is pressed downwardly in the groove with the edge thereof extending horizontally, the frictional engagement between the driving member and the roller is increased.

2. A device as set forth in claim 1 in which the rotatable driving member comprises an upright open vessel and the driven roller is adapted to frictionally engage the upper edge of the vessel, and said means for resiliently mounting the element being so constructed and arranged that, when a knife is pressed downwardly in the groove with the edge thereof extending horizontally, the frictional engagement between the vessel and the roller is increased, the roller having its axis of rotation substantially perpendicular to a plane bisecting the groove and passing through the apex thereof.

3. A device as set forth in claim 1 in which said element comprises a bracket having two spaced apart arms disposed in planes substantially perpendicular to one another, the roller and disc structure being rotatably carried by one of the arms, and means for resiliently mounting the other arm so that, when a knife is pressed downwardly in the groove with the edge thereof extending horizontally, the frictional engagement between the driving member and the roller is increased.

4. A device for sharpening cutlery, such as a knife, for example, comprising a rotatable driving member, a driven roller which is adapted to frictionally cooperate with the driving member, grinding disc structure connected to the driven roller constructed to provide an annular groove having opposing faces containing abrasive material, an element upon which the roller is rotatably mounted, and means for resiliently mounting the element so that, when a knife is pressed downwardly in the groove with the edge thereof extending horizontally, the frictional engagement between the driving member and the roller is increased.

5. A device as set forth in claim 4 in which the rotatable driving member comprises an upright open vessel and the driven roller is adapted to frictionally engage the upper edge of the vessel, and said means for resiliently mounting the element being so constructed and arranged that, when a knife is pressed downwardly in the groove with the edge thereof extending horizontally, the frictional engagement between the vessel and the roller is increased, the roller having its axis of rotation substantially perpendicular to a plane bisecting the groove and passing through the apex thereof.

6. A device as set forth in claim 4 in which said element comprises a bracket having two

spaced apart arms disposed in planes substantially perpendicular to one another, the roller and disc structure being rotatably carried by one of the arms, and means for resiliently mounting the other arm so that, when a knife is pressed downwardly in the groove with the edge thereof extending horizontally, the frictional engagement between the driving member and the roller is increased.

10. 7. A device for sharpening cutlery, such as a knife, for example, comprising a support, a rotatable driving member carried by the support, a driven roller which is adapted to frictionally cooperate with the driving member, grinding disc structure connected to the driven roller constructed to provide an annular groove having opposing faces containing abrasive material, a bracket having two spaced apart arms disposed in planes substantially perpendicular to one another, the roller and disc structure being rotatably carried by one of the arms, a part mounted on said support which is formed with a recess, and means including a sleeve member disposed about the other arm which is adapted to fit snugly in the recess for resiliently mounting the bracket so that, when a knife is pressed downwardly in the groove with the edge thereof extending horizontally, the frictional engagement between the driving member and said roller is increased, the sleeve member being elongated and having a longer contact surface with the other arm than with the wall of the recess.

8. A device for sharpening cutlery, such as a knife, for example, comprising a supporting base, a rotatable driving member carried by the base, a driven roller which is adapted to frictionally cooperate with the driving member, grinding disc structure connected to the driven roller constructed to provide an annular groove having opposing faces containing abrasive material, a bracket having two spaced apart arms disposed in planes substantially perpendicular to one another, the roller and disc structure being rotatably carried by one of the arms, a part mounted on the base which is formed with a recess, and means including a sleeve member disposed about the other arm which is adapted to fit snugly in the recess for resiliently mounting the bracket so that, when a knife is pressed downwardly in the groove with the edge thereof extending horizontally, the frictional engagement between the driving member and the roller is increased.

9. A device as set forth in claim 8 in which the sleeve member is formed of material possessing sufficient resiliency to enable the roller to be brought into good frictional engagement with the driving member.

10. A kitchen utility appliance comprising a base, a driving member carried by the base comprising an upright vessel rotatable about a vertical axis, a driven roller which is adapted to frictionally cooperate with the vessel, a rotatable element connected to the driven roller, a bracket having spaced apart end portions, the roller and element being rotatably carried by one of the end portions, and means associated with said base for supporting the other end portion of the bracket at a region outside the vessel and about which region said bracket is movable, said bracket and supporting means being so constructed and arranged that, when the driven roller is moved into frictional engagement with the vessel while the latter is rotating, rotating movement is imparted to the rotatable element about an axis at an angle with respect to the vertical axis of rotation of the vessel.

11. A kitchen utility appliance as set forth in claim 10 in which said bracket and supporting means are so constructed and arranged that the driven roller is adapted to be moved into frictional engagement with an exterior surface of the vessel to impart rotating movement to the element connected to the roller.
